UNITED STATES PATENT OFFICE.

ARCHIBALD M. WHIPPLE, OF NORTH ADAMS, MASSACHUSETTS, ASSIGNOR OF THREE-FOURTHS TO WILLIAM W. ANTHONY AND GEORGE N. RICH, OF SAME PLACE, AND E. A. CARLISLE, OF BOSTON, MASSACHUSETTS.

WINDOW.

SPECIFICATION forming part of Letters Patent No. 656,130, dated August 14, 1900.

Application filed November 6, 1899. Serial No. 735,866. (No model.)

To all whom it may concern:

Be it known that I, ARCHIBALD M. WHIPPLE, a citizen of the United States, residing at North Adams, county of Berkshire and State of Massachusetts, have invented certain new and useful Improvements in Windows, of which the following is a specification.

The invention relates to such improvements; and it consists of the novel construction and combination of parts hereinafter described and subsequently claimed.

Reference may be had to the accompanying drawings, and the reference characters marked thereon, which form a part of this specification.

Similar characters refer to similar parts in the several figures.

Figure 1 of the drawings is a front side elevation of my improved window. Fig. 2 is a vertical section of the same, taken on the broken line 2 2 in Fig. 1. Fig. 3 is a top plan view of the upper end of the sash. Fig. 4 is a side view of the slat for closing the open slot in the upper rail. Fig. 5 is a horizontal section taken on the broken line 5 5 in Fig. 2. Fig. 6 is a similar section with the glass and packing removed. Fig. 7 is a similar section showing a modified form of packing groove or rabbet.

The object of my invention is to afford a stronger and more ornamental and durable means for glazing window-sashes and by which the glazing can be more easily accomplished and removed without the necessity of skilled labor.

Heretofore the glass has commonly been secured in window-sashes by means of metal points, such as triangular pieces of sheet-tin, and putty. Extreme care and skill are required lest the metal points, being applied only at widely-separated intervals, should crack the glass and lest the putty should present an uneven and objectionable appearance. Expansion and contraction of the parts due to changes in temperature are liable to increase the pressure of the points upon the glass sufficiently to crack it.

In factory buildings and other buildings or structures where the windows are subjected

to a considerable or continuous vibration the 50 putty soon disintegrates and falls away from the sash as heretofore constructed, which not only destroys the tight joint between the glass and frame, but puts more strain upon the metal points, which soon yield and allow the 55 glass to be broken. My improved construction overcomes these defects, doing away with the metal points and permitting the use of any desired packing. I provide the stiles and rails of the sash with channels adapted 60 to receive and loosely fit the edges of the glass, the channel in one of the stiles or rails (preferably in the top rail) being extended through the rail to form a slot opening exteriorly of the rail and communicating therethrough 65 with the glass-channels in the adjacent sides of the frame, through which slot the glass can be easily slid into the sash and into the channels made to receive it. Along one edge of the channel in the respective parts I provide 70 a rabbet or groove adapted to receive a cord packing which is forced in between the outer wall of the groove and the glass, thus not only securely fastening the glass against lateral movement in the loosely-fitting channel, 75 but providing an elastic resistance to such movement which would yield to the forces of expansion and which affords approximately-equal resistance at every point along the edge of the glass. By making the cord impervious 80 to water by a treatment of oil and lead it will make a tight joint and will not be materially affected by changes in temperature or vibrations. After insertion the cord can be painted or otherwise treated with covering material. 85

I make no claim in this application to any particular kind of packing nor to the method of making same.

Referring to the drawings, the numeral 1 represents the stiles, and 2 the rails, of the 90 window-sash, which may be put together and secured in the usual manner. The rails and stiles are each provided with a channel 3, adapted to receive and loosely fit the glass 4, as seen in Figs. 5 and 7. The channel is extended entirely through the top rail to form the open slot 5, through which the glass is inserted in the sash to the position shown in 95

Fig. 2. After the glass is inserted the open slot may be closed and the glass held in place by the insertion of a slat 6, as shown in Fig. 2. After the glass is inserted the cord packing 5 is inserted in the rabbet or groove 8, so as to force the glass over against the opposite wall of the channel and make a tight joint between the glass and sash.

The rabbet or groove may be right-angular 10 in cross-section, as shown in Figs. 5 and 6, or curved and undercut, as shown in Fig. 7. By having the groove undercut or coped out the packing is held more securely in place; but either form or any approximate form will 15 be found amply sufficient to hold the packing against displacement.

It is obvious that the channel is not obstructed by or made to receive anything but the glass, so that the glass if cracked or 20 broken can be easily removed and another inserted through the open slot, it only being necessary to remove the slat 6 and the packing-cord, which can be easily replaced as well as removed.

25 By having a distinct channel for the glass and groove for the packing, with the channel extended more deeply into the sash-frame than the groove and the groove opening laterally into the channel, I secure many advantages.

30 The glass is not wholly dependent upon the packing for support, and if the packing were entirely removed the glass could not fall from the sash nor have any considerable movement.

35 The glass forms one side of the packing-groove, and the outer wall of the groove is located in direct opposition to the glass, but at a distance from the edge of the glass, so 40 that none of the packing material can come in contact with either the edge of the glass or the bottom of the channel, which is an important feature, especially if the packing material is of a sticky or adhesive nature, as 45 the edge of the glass and the channel are thus kept at all times entirely unobstructed and free from packing material, which would tend to clog the narrow channel and interfere with the insertion and removal of the 50 glass.

55 Only a small quantity of packing is necessary if properly applied and supported, and in the present construction the packing-groove can be made as shallow as desired to receive the comparatively-small quantity of packing that will be found necessary, while the glass-channel can be made of any depth desired and the glass can be thus deeply seated in the frame.

60 The packing can, if desired, be almost wholly concealed within its groove and where exposed will be hardly noticeable, particularly if painted similarly to the sash-frame.

65 The wall of the glass-receiving channel on the side opposite the packing-groove is preferably extended to approximately the same distance from the bottom of the channel as

the opposite wall of the packing-groove, whereby said extended channel-wall will support the body of the glass at a distance from 70 its edge in direct opposition to the packing.

I am aware that weather-strips and the like have been applied to a sash-frame in contact with the glass and that it has also been proposed to secure a rubber or other packing 75 cord in contact with the glass by means of grooved metal strips seated in slots cut in the frame of the sash, and I make no claim to either of such constructions, in none of which did the sash-frame have a distinct glass-receiving channel extended more deeply into the frame than the groove or seat for the packing. Furthermore, the construction employing the metal strips above referred to 80 could not be applied to a frame having narrow rails nor to the mullions, as the narrow rail or mullion would be almost or quite cut through by the grooves necessary to receive such metal strips.

Most or all of the prior attempts to improve 85 upon the common method of securing glass in windows have been confined to the formation of a joint between the outer side of the glass and the sash-frame by actual contact of the glass with the wood of the frame, the 95 pressure being applied by packing-strips upon the inner side of the glass. A tight joint cannot thus be formed on account of the irregularities in the surface of the glass.

In my improved construction it is more particularly intended to locate the packing on the outer side of the glass, and thus, by using an impervious plastic packing that will conform to the irregularities in the glass, to secure a tight joint that will be proof against 100 air and water without injurious pressure upon the glass.

105 What I claim as new, and desire to secure by Letters Patent, is—

1. In a window, the combination with the 110 sash-frame having formed therein a glass-receiving channel and a packing-groove, opening into said channel, said channel being extended more deeply into the frame than said groove; of a glass located in said channel; 115 and packing located in said groove, in contact with the glass, substantially as described.

2. In a window, the combination with the 120 sash-frame having formed therein a glass-receiving channel and a packing-groove, said channel being extended more deeply into the frame than said groove; of a glass located in said channel; and packing inserted in said 125 groove and inclosed between the outer wall of the groove and the body of the glass at a distance from its edge, substantially as described.

3. In a window the combination with the 130 sash-frame having formed therein a glass-receiving channel on three sides of the glass-opening, a slot in the fourth side of the frame opening exteriorly thereof and communicating directly with said glass-channel, and a packing-groove on all sides of said glass-open-

ing, said channel being more deeply extended into the frame than said groove; of a glass located in said channel in position to close said glass-opening; means for closing said slot in the fourth side of the frame; and packing inserted in said groove, substantially as described.

4. In a window, the combination with the sash-frame having formed therein a glass-receiving channel, and a packing-groove, said channel being extended more deeply into the frame than said groove, and the opposing

walls of said channel and groove being extended to approximately the same distance from the bottom of said channel; of a glass located in said channel; and packing located in said groove opposite the extended portion of the channel-wall, substantially as described. 15

In testimony whereof I have hereunto set my hand this 28th day of October, 1899.

ARCHIBALD M. WHIPPLE.
